FIG. 1.

FIG. 2.

Irvine R. Dean
Inventor

By George Kimmel.

Attorney

UNITED STATES PATENT OFFICE.

IRVINE R. DEAN, OF MEMPHIS, TENNESSEE.

TOY REBOUNDER.

1,204,957.

Specification of Letters Patent. Patented Nov. 14, 1916.

Application filed July 24, 1916. Serial No. 111,000.

To all whom it may concern:

Be it known that I, IRVINE R. DEAN, a citizen of the United States, and resident of Memphis, in the county of Shelby and State of Tennessee, have invented certain new and useful Improvements in Toy Rebounders, of which the following is a specification.

The present invention relates to the class 10 of games and toys and has particular reference to new and useful improvements in toy rebounders employing a ball and bat, the primary object being to provide a novel toy of the class described requiring skill to use, 1. as well as being interesting.

Another object of my invention is to provide a toy rebounder of the class described which is simple in construction, may be cheaply manufactured and will afford considerable amusement to those using the same.

Other objects and advantages to be derived from the use of my improved toy rebounder will appear from the following detail description and the claims, taken with 25 an inspection of the accompanying drawing, in which:

Figure 1 is a perspective view of a toy embodying the improvements of my invention; and Fig. 2 is an enlarged fragmental 30 longitudinal sectional view of the same.

Referring more particularly to the drawing, wherein similar characters of reference designate like and corresponding parts throughout the various views, 1 designates 35 the handle of my improved toy, the same having a recess 2 therein adjacent one end thereof, said recess being adapted to receive a rebounding board 3, said board being seated in the recess and retained therein by 40 means of nails 4 or the like. A ball 5 carried by the free end of an elastic strip 6 is provided, said strip being secured at the center of the board 3 by means of a nail 7 or the like.

45 A bell 8 or similar sounding device is mounted on the free end of the handle 1 adjacent the board 3, said bell being secured in position by means of a nail or spike 9.

In using my improved toy the object is to 50 cause the ball to rebound against the board 3 continuously. In actual use this will be

found to require skill, it being particularly difficult to prevent the ball from striking the bell. By using my improved toy a game of skill may be played between a number 55 of players, the object being to determine the winner by the least number of rings of the bell. It will, therefore, be seen that I have provided a simple and novel toy which is amusing to those using the same to play a 60 game.

From the above description taken in connection with the accompanying drawing, it is thought that a clear and comprehensive understanding of the construction, operation 65 and advantages of my invention may be had, and while I have shown and described the device as embodying a specific structure, I desire that it be understood that such changes may be made in said structure as 70 do not depart from the spirit and scope of the invention as claimed.

Having thus fully described my invention, what I claim as new and desire to secure by Letters Patent, is:—

75 1. A toy of the class described, including a handle portion, provided with a recess, a board arranged transversely of said handle in said recess, a ball suspended from said board by an elastic means, and a bell or other sounding device carried by the free end of said handle.

2. A toy of the class described, including a handle having a recess adjacent one end thereof, a transversely mounted board in 85 said recess, an elastic strip extending from the central portion of said board and carrying a ball or similar rebounder on the free end thereof, and a bell carried by the free end of said handle.

90 3. A toy of the class described, including a handle having a recess therein adjacent one end thereof, a board arranged transversely of said handle in said recess, a bell carried by the free end of said handle, a ball, elastic means connecting said ball with said board, and means for maintaining said board on said handle.

In testimony whereof, I affix my signature hereto.

IRVINE R. DEAN.
